UNITED STATES PATENT OFFICE.

JOSEPH D. WOOD, OF QUINCY, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

TRIPPING DEVICE FOR ELECTRIC SWITCHES.

Application filed November 3, 1924. Serial No. 747,479.

This invention relates to opening devices for electric switches and has particular reference to devices adapted to open the switch upon diminution or failure of load, or potential, in the circuit controlled by the switch.

Devices of the type above set forth usually comprise a solenoid having an armature adapted normally to be held in raised position and to be released and drop and thereby effect the opening of the switch when the current traversing the solenoid becomes diminished to such a point that the solenoid is unable to sustain the weight of the armature. The weight of the armature usually is depended upon to actuate the opening of the switch and, ordinarily, the armature is caused to act directly upon the locking device of the switch. For many reasons it is desirable to have an armature of light weight, as, for instance, in order that the device may operate within rather close upper and lower limits of energization of the solenoid. A light weight armature, however, ordinarily is not heavy enough by its own weight to actuate the locking device of the switch and, if a long extent of travel of the armature is permitted in order to strike a hammer blow upon the switch locking device, it is difficult to effect the operation of the apparatus within its desired close limits.

Consequently, it is an object of this invention to provide a device of the type described with a source of power adapted to effect the opening of the switch and so arranged that the armature need have only the relatively small weight required to control the release of the source of power.

A further object is generally to improve the construction and operation of tripping devices for electric switches.

Fig. 1 is a plan view of a switch-tripping device embodying the invention.

Fig. 2 is a vertical sectional elevation along lines 2—2 of Fig. 1.

Fig. 3 is a plan section along lines 3—3 of Fig. 2.

Fig. 4 is a side elevation.

Fig. 5 is a perspective detail of the operating toggle of the energy storing device.

That embodiment of my invention herein illustrated comprises a casing composed of an upper section 10 and a lower section 12 secured removably together by suitable

means as screws 14. Both sections preferably are formed of iron or some other suitable magnetic material. The upper casing-section 10 is more or less cylindrical in form and is provided with the internal recess 16 adapted to contain a solenoid 18. Said solenoid 18 is formed upon a vertically disposed tube 20 and a core piece 22 is carried by the casing 10 and fits within the upper end of said tube. A lateral opening 24 is formed through the side wall of said casing 10 at the lower end thereof to provide means for the passage of the solenoid leads therethrough. A guard wall 26 may extend laterally from said casing and be disposed to surround said opening 24.

The lower casing-section 12 is formed with a circular recess 28 which is adapted to conform and be complementary with the recess 16 and form a partial enclosure for the solenoid 18. The lower and solenoid-supporting wall 30 of said recess is formed with an aperture 32 therein which is disposed co-axial with the solenoid tube 20 and an armature or core 34 is freely disposed within said solenoid tube 20 and is adapted normally to be supported in raised position, as illustrated in Fig. 2, when the solenoid winding is normally energized. When the solenoid winding becomes de-energized or insufficiently energized said armature 32 is adapted to fall downwardly in the tube 20, thereby to actuate the tripping device of the switch.

The source of power for tripping the switch is contained in a lower compartment 36 of the lower casing-section 12. Said source of power includes an energy-storing device comprising a tensile spring 38, which spring is adapted to have ample power to operate the tripping device of the switch. Said spring is detachably connected at one end with a lug 40 of the lower casing 12. The other end of said spring is reflexed and extended through an aperture 42 in a lug 44, which lug is extended laterally from a crank-arm 46 of a bell-crank lever. Said bell-crank lever is fixed to and is adapted to rotate a shaft 48, which shaft is journalled in a hub 50 of the casing and extends laterally outward beyond the casing. The normal relation of said bell-crank lever and spring is such that said spring is under tension and is disposed constantly to urge said shaft for

rotation thereby to trip the switch and, to this end, the arm 46 is restrained releasably in such a position that said spring is slightly off the center of the shaft 48 and is thereby disposed to rotate said bell-crank lever in a counter-clockwise direction when so permitted. The above construction provides a toggle comprising a strut-member and a resilient member, in which toggle the crank-
10 arm 46 forms the strut-member and the spring 38 forms the resilient member

Means are provided normally to restrain the spring and bell-crank lever in the afore-said relation. Said means include a locking lever 51, which lever is disposed beneath said bell crank lever and is fixed to a shaft 52, which shaft 52 is journalled in the opposite side walls of the casing 12. Said lever 51 is extended to a suitable point beneath and in the path of movement of the free core 34 of the solenoid and is adapted to be depressed by the weight of said core. Said bell crank lever is formed or provided with two spaced and downwardly extended arms 53
20 which are disposed on opposite sides of said locking lever 51. A roller 54 is disposed in the space between said arms and is pivoted on a pin 56 passed through and secured in said arms. Said roller 54 is adapted normally to engage a recess 58 in said locking lever 51 and the arrangement and disposition of said roller and locking lever 51 is such that said lever normally serves to restrain the bell-crank lever from movement
30 due to said spring 38. When, however, the armature 34 drops and depresses said lever 51, the bell-crank lever is released and the shaft thereby is free to rotate in a counter-clockwise direction under the influence of
40 said spring 38.

Yielding means as a tensile spring 60 serves normally to urge said locking lever 51 towards a position for locking engagement with the bell-crank lever. The tension
45 of said spring, however, is adapted to be sufficiently weak to permit said locking lever to move downwardly due to the direct weight of the armature upon it.

An actuator-member as a trip arm 62 may be fixed to the outer end of said shaft 48 and is adapted to be disposed in tripping relation with the locking device 49 of a switch
50 61 as is illustrated diagrammatically in Fig. 4.

55 After the mechanism has once operated to trip the switch, it must be reset. For this purpose, said tripping arm 62 is provided with a manually-engageable handle 64 by which the shaft and the bell-crank lever may be rotated in a clockwise direction thereby to re-establish the stress in, or "cock", the spring 38 and restore the mechanism in condition for further operation.

60 With the device here shown, the weight
65 of the core 34 has merely to overcome the

relatively small amount of resistance present in removing the lock on the spring 38; and said spring may be provided with ample power to trip the switch without opposing undue resistance to the operation of its locking mechanism.

The structure may be otherwise modified without departing from the spirit of the invention.

I claim:

1. An attachment for an electric switch including the combination of an enclosing casing, a normally-energized solenoid contained in the upper part of said casing and having a free armature normally supported in raised position, an external actuator-member carried by said casing, operating mechanism therefor disposed in the lower part of said casing and comprising a pivoted arm connected with said actuator-member, a stretched spring extended by and close to the pivot and connected with the free end of said arm, restraining means for said energy-storing device having a component disposed beneath and normally free of said armature and arranged to be actuated by the weight thereof to release said energy-storing device for operation, and manual resetting means for said energy-storing means disposed externally of said casing.

2. A tripping device for an electric switch comprising the combination of a pivoted arm, a latch normally arranged in holding engagement with said arm and an actuating spring for said arm connected therewith at its free end and in the latched position of said arm normally occupying a position close to but slightly to one side of the pivot point of said arm, said arm thus taking practically all of the tension of said spring and relieving said latch of the greater part of the spring tension, said arm when released by said latch being moved about its pivot by said spring and said spring by such movement being moved away from the pivot of said arm, and tripping means for the latch.

3. A tripping device for an electric switch having the combination of a pivoted arm, a spring extended by and close to the pivot and connected with the free end of said arm, a latch normally engaging said arm and tripping means for the latch.

4. The combination of a normally-energized solenoid having a free armature normally supported in raised position, a pivotally-mounted bell-crank lever having two angularly-related arms, a spring connected with one of said arms and extended by and close to the pivot of said lever, a pivoted locking lever having means to engage said other arm of said bell-crank lever and restrain it from rotation, said locking lever having a component disposed beneath and normally free of said armature and adapted to be depressed by the weight thereof to re-

lease said bell-crank lever for rotation, and yielding means constantly urging said lever towards locking position.

5. The combination of a normally-energized solenoid having a free armature normally supported in raised position, an actuator-device including a shaft, an actuator-arm fixed to said shaft, a bell-crank lever also fixed to said shaft, a tension spring connected with one of the arms of said bell-crank lever and arranged constantly to urge it and said shaft for rotation, a locking lever engageable with the other arm of said bell-crank lever to restrain it against rotation 10 and having a component thereof extended beneath and in position to be depressed by the weight of said free armature, whereby to release said bell-crank lever for rotation, and yielding means constantly urging said locking lever toward locking position.

6. The combination of a normally-energized solenoid having a free armature supported in raised position, an actuator-device including a shaft, an actuator-arm fixed to 25 said shaft, a tension spring connected with one of the arms of said bell-crank lever and arranged constantly to urge it and said shaft for rotation, a locking lever engageable with the other arm of said bell-crank lever to restrain it against rotation and having a component thereof extended beneath and in position to be depressed by the weight of said free armature, whereby to release said bell-crank lever for rotation, yielding means 30 constantly urging said locking lever toward locking position, and manual means to rotate said bell-crank lever against the action of said spring.

7. The combination of a normally-energized solenoid having a free armature normally supported in raised position, an actuator-device including a shaft, an actuator-arm fixed to said shaft, a crank-arm also fixed to said shaft, a tensile spring connected 45 with said crank-arm and arranged constantly to urge said shaft for rotation, a pair of spaced arms fixed to said shaft, a latch-roller pivotally mounted between said arms, a locking lever disposed beneath said roller 50 and having a recess adapted normally to receive said roller, whereby to restrain said shaft against rotation, said locking lever having a component disposed beneath said armature and adapted to be depressed by the 55 weight of said armature, thereby to dis-

engage with said roller, yielding means constantly urging said locking lever toward engaging relation with said roller, and manual means to rotate said shaft against the action of said spring, whereby to reset the device. 60

8. The combination of a casing having upper and lower detachable sections, a solenoid contained mainly in said upper casing-section and having a free armature normally supported in raised position, a shaft journalled in said lower casing-section beneath said solenoid and extended outwardly beyond the casing, an arm fixed to said shaft, a crank-arm disposed within said casing and fixed to said shaft, a tensile spring connected 65 with said arm and arranged constantly to urge said arm and shaft for rotation, and means normally to restrain said arm and shaft from such rotation including a second arm fixed to said shaft, a roller carried by 70 said arm, a locking lever pivoted below said roller and located to engage therewith, whereby to restrain said shaft from rotation, said locking lever disposed beneath said armature and adapted to be depressed by 75 the weight thereof, whereby to release said roller and permit the shaft to be rotated, and yielding means constantly urging said locking lever toward locking engagement with said roller.

9. The combination of a casing having upper and lower detachable sections, each provided with complementary recesses therein, a solenoid contained in said recesses, said lower casing having a solenoid-supporting 80 wall at the bottom of its recess provided with an aperture, a free armature adapted normally to be supported in raised position within said solenoid and drop through said aperture when said solenoid is de-energized, 85 a shaft journalled in and extended through said lower casing-section, an actuating-arm fixed to the extended end of said shaft, energy-storing means associated with said shaft and arranged constantly to urge said shaft for rotary movement, and restraining means for said energy-storing means having a component disposed beneath said aperture in position to be depressed by the weight of said armature, whereby to release 90 said energy-storing means to rotate said shaft.

In testimony whereof, I have signed my name to this specification.

JOSEPH D. WOOD.
